UNITED STATES PATENT OFFICE.

THEODORE S. ETHERIDGE, OF GRAND RAPIDS, MICHIGAN.

PAMPHLET-COVERING MACHINE.

1,274,154.

Specification of Letters Patent. Patented July 30, 1918.

Application filed March 31, 1917. Serial No. 158,986.

To all whom it may concern:

Be it known that I, THEODORE S. ETHERIDGE, a citizen of the United States of America, residing at Grand Rapids, in the 5 county of Kent and State of Michigan, have invented certain new and useful Improvements in Pamphlet-Covering Machines; and I do hereby declare the following to be a full, clear, and exact description of the invention, such as will enable others skilled in the art to which it appertains to make and use the same.

This invention relates to improvements in book covering devices and more particularly 15 to a device to aid and expedite the customary hand process of applying glued covers to books, pamphlets and the like and its object is to provide a device which will accommodate and operate upon books and 20 covers of various dimensions and will effectively perform the operations of locating the book in its proper position relative to the cover and of affixing the cover to the book after the glue has been applied to the 25 cover or the book.

In the art of bookbinding wherein the covers are affixed to the books by gluing them along the back portion of the book, a large part of the work has been done here- 30 tofore by hand, this being necessarily slow and subject to inaccuracy of the operator. The device embodying this invention is adapted to greatly facilitate and expedite the hand method of affixing the cover to the 35 book and has for its primary object and purpose the provision of novel means to this end.

The device is also provided with various 40 useful features of construction and arrangement whereby it may be readily adjusted to receive and operate upon books and covers varying in dimensions from the smallest to the largest customarily used as hereinafter more fully described and definitely pointed 45 out in the claims. The preferred construction of this device is shown in the accompanying drawings in which:—

Figure 1 is a perspective view of a device embodying this invention showing a cover 50 sheet and book in their relative positions at one point of the operation.

Fig. 2 is a plan view of the device shown

in Fig. 1, parts being broken away and partially in section.

Fig. 3 is an enlarged sectional elevation 55 taken longitudinally through the die with parts broken away.

Fig. 4 is a sectional elevation transversely of the die with parts broken away.

Fig. 5 is an inverted plan of the middle 60 part of the device with parts broken away showing the means for adjusting one vertical side of the die.

Fig. 6 is a transverse section through a 65 part of the device illustrating the manner in which the cover is folded over the back of the book.

Fig. 7 is a longitudinal sectional detail 70 showing the books in engagement with the pressure roller.

Fig. 8 is a sectional detail of the adjustable book guide and cover stop.

Fig. 9 is a plan view of the device showing 75 a modification of the book guides.

Fig. 10 is a side elevation of the same, 80 and

Fig. 11 is a partial front elevation of the same.

Like numbers refer to like parts throughout the different views of the drawing. 85

1 represents the table divided near its middle providing an elongated opening 2 extending from front to rear of the device. The table is supported by a frame 3 beneath it. The frame has an elongated bed 4 extending longitudinally of the opening 2, and beneath the plane of the table 1 to serve as the bottom of the die. The vertical sides 5 and 6 of the die are mounted upon the bed 4 and lie within the opening 2, extending the 90 entire length of the same and projecting past the forward edge of the table. The inner vertical faces of these sides extend vertical for a part of their width and are thence curved divergently.

The side 5 is slidably mounted upon the bed 4 being held in place by studs 7 passing through lugs 9 on the bed and having heads 8 upon their outer ends which engage the lugs and limit the movement toward the 100 side 6. Springs 10 surrounding the studs 7 engage respectively the side 5 and the lugs 9 yieldably forcing the side 5 toward the side 6.

The die side 6 is slidably mounted upon the bed 4 and movable toward and from the side 5 being maintained in parallel relation thereto. For this purpose feet 11 are provided on the side 6 having slots 12 extending transversely of the die and studs 13 attached to the bed extend through the slots 12 and traverse the same.

Studs 15 attached to and projecting from the under side of the feet extend through and traverse transverse slots 14 in the bed 4 and also extend through and traverse inclined cam slots 16 in a plate 17 longitudinally movable on the under side of the bed. The plate 17 is also provided with longitudinal slots 18, and studs 19 are attached to the under side of the bed and extend through the slots 18 causing the plate to travel in a true longitudinal direction. The plate 17 is actuated by a screw 20 engaging a threaded lug 21 on the plate and having a bearing in a lug 22 which projects from the bed and a knob 23 is provided on the outer end of the screw whereby it may be manually turned.

It will be seen that longitudinal movement of the plate 17 by means of the screw 20 causes the studs 15 to be moved transversely as they traverse the inclined cam slots 16, thus moving the die side 6, to the feet 11 of which the studs 15 are attached, toward or away from the opposite side 5 in parallel relation thereto.

As a back stop for the cover sheet 24 a bar 26 extends transversely across the entire width of the table in contact therewith being attached preferably by screws 27 so that it may be moved and attached at various positions on the table, it being desirable to locate it near the front for narrow books and near the back for wider ones. To adjust the cover sheet in lateral position a stop 28 is provided being adjustably mounted near one end of the bar 26 by means of a screw 29 extending through a slot 30 in the body of the stop. Various threaded holes 31 are provided in the bar 26 to receive the screw 29 and increase the range of adjustment of the stop 28.

The book 25 is guided into contact with the cover sheet by means of a back stop 32 extending vertically from the middle position of the bar 26 and by wings 33 and 34 divergingly from the forward face thereof.

The back stop 32 is clamped to the bar 26 by the screw 35 which extends through a slot 36 in the base of the back stop. This stop may be adjusted so that its vertical face will come flush with the edge of the bar 26 which forms a stop for the cover sheet or it may be extended beyond the edge of said bar as shown in Fig. 8 when it is desirable to have the cover overhang the edge of the book. The wing 33 is fixed to the stop 32 so that its vertical face will

stand in alignment with the inner face of the die side 5 when said side is in normal position. The wing 34 is slidably mounted on the stop 32 and clamped by the screw 37 extending through the slot 38 in said stop and may be adjusted to align with the die side 6 as said side is adjusted to accommodate books of various thicknesses.

Elongated guides 33^a and 34^a as shown in Figs. 9, 10 and 11 may be substituted for 33 and 34. These elongated guides serve to guide the book more accurately to contact with the cover sheet. One of these guides such as 33^a may be omitted entirely in which case the remaining one serves as a stop to engage one side of the book and thus guide it to its proper location. Beneath the forward projecting ends of the die sides 5 and 6 a pressure roller 39 is located to engage the back of the covered book as it is drawn from the device. This roller extends transversely of the die and is located with the upper part of its periphery slightly above the plane of the bed 4. It is preferably provided with a resilient face such as rubber or felt and is freely rotatable on its axis 40, being journaled in extensions 41 on the base 4.

Flat springs 42 are attached in recesses 43 near the forward ends of the inner faces of the die sides 5 and 6 and their free ends normally project beyond the faces of the die sides above the roller 39. These jaws exert an additional lateral pressure upon the sides of the covered book near the back thereof as it is being drawn over the roller 39.

In operating this device the glue is first applied either to the back of the book or to a portion 24^a of the cover sheet 24 and the cover sheet is then placed upon the table 1 and located by the bar 26 and lateral stop 28 so that the portion 24^a, which is to come adjacent and be glued to the back of the book, will lie over the opening in the die and beneath the guide wings 33 and 34. The book is then held vertically with its rear end against the stop 32 and between the guide wings 33 and 34, its forward end being guided by hand, and it is brought into engagement with the cover sheet and forced downward into the die carrying the cover sheet; with and by the spring pressure of the side 5 of the die and friction of the cover sheet between the two sides 5 and 6 the back of the book is squeezed tightly together and the cover stretched tightly over it and folded evenly over the corners. The book and cover are then moved longitudinally from the die, the back riding over the roller 39, thereby causing the cover to be pressed snugly against the back, the springs 42 at the same time engaging against the sides of the cover near the back and pressing the cover sides at such points against the book.

The springs 42 are especially desirable where the cover is glued, not only to the back of the book but also to narrow portions of the sides near the back as is often done.

I claim:—

1. A book covering appliance comprising a horizontal cover support, a die beneath the cover support to receive the back of the book and the cover and a roller extending transversely of the die and having the upper part of its periphery substantially in the plane of the die bottom and adapted to engage the back of the covered book as it is moved longitudinally in the die.

2. A book covering appliance comprising a horizontal cover support, a die beneath the cover support to receive the back of the book and the cover, a roller extending transversely of the die and substantially in the plane of its bottom to engage the back of the covered book as it is moved longitudinally of the roller, means for locating the cover upon the cover support and means for guiding the uncovered book into engagement with the cover.

3. A book covering appliance comprising a horizontal support for the cover, a die beneath the cover support to receive the back of the book and the cover, a stop extending transversely across the support to be engaged by one end of the cover, a side stop transversely adjustable of the said cover support to be engaged by one side of the cover, a vertical stop in alinement with the first named stop and located above the die to be engaged by one end of the uncovered book and a guide extending horizontally above the cover support and spaced apart therefrom and in vertical alinement with the die to guide the uncovered book into engagement with the cover.

4. A book covering appliance comprising a horizontal cover support, a die beneath the cover support to receive the back of the book and the cover, a stop extending transversely of the cover support to be engaged by one end of the cover, a side stop adjustable transversely of the said support, a vertical stop over the die and in alinement with the first named stop, and transversely adjustable guides extending horizontally above the cover support and spaced away from the same to receive the uncovered book between them and guide it into engagement with the cover.

5. A book covering appliance comprising

a horizontal cover support, a die beneath the cover support to receive the back of the book and the cover, a transversely extending stop on the cover support to be engaged by one end of the cover, and a vertical stop to be engaged by one end of the uncovered book said vertical stop being located above the transverse stop and over the die and adjustable transversely of the transverse stop so that it may be brought in vertical alinement therewith or extended beyond the same.

6. A book covering appliance comprising a die to receive a book and cover to form the cover over the back of the book and flat springs attached one to the inner face of each of the sides of the die and yieldably projecting therefrom to engage the cover at the sides of the book near its back as said book and cover are moved longitudinally in the die.

7. A book covering appliance comprising a die to receive a book and a cover to form the cover over the back of the book said die having a bottom and vertical sides which project at one end beyond said bottom, a transversely extending roller beneath the projecting ends of said sides and substantially in the plane of the bottom and flat springs one on the inner surface of each side of the die yieldably projecting therefrom over the said roller.

8. A book covering appliance comprising a die to receive a book and a cover to form the cover over the back of the book said die having a bottom and spaced apart vertical sides one of which is adjustable laterally relative to the other and means for moving said adjustable side comprising a plate longitudinally movable on said die bottom and having oblique cam slots therein, a screw to move said plate, means for guiding said adjustable side in its lateral movement and studs fixed to said side and extending through the cam slots in the plate.

9. A book covering appliance comprising a horizontal slotted cover support, a die located below and paralleling the slot in said support, means adjustably connected to the cover support for locating different widths of covers with respect to the die and guiding means adjustably mounted on the support on each side of said slot for guiding the uncovered book into engagement with the cover.

In testimony whereof I affix my signature.
THEODORE S. ETHERIDGE.
